UNITED STATES PATENT OFFICE.

HENRY F. SCHMIDT, OF PITTSBURGH, PENNSYLVANIA, ASSIGNOR TO WESTINGHOUSE ELECTRIC & MANUFACTURING CO., A CORPORATION OF PENNSYLVANIA.

TURBINE.

1,424,263.

Specification of Letters Patent. Patented Aug. 1, 1922.

Application filed June 13, 1918. Serial No. 239,810.

To all whom it may concern:

Be it known that I, HENRY F. SCHMIDT, a citizen of the United States, and a resident of Pittsburgh, in the county of Allegheny and State of Pennsylvania, have made a new and useful Invention in Turbines, of which the following is a specification.

This invention relates to turbines and has for an object to produce a new and improved 10 turbine capable of developing more power than other turbines of the same type and size now in use and known to me.

A further object is to produce a new and improved turbine which operates with 15 higher efficiency, over a wider range of loads, than other turbines of the same type now in use and known to me.

A further object is to produce a new and improved reentry turbine in which auxiliary 20 nozzles are placed opposite what is ordinarily considered the ineffective portion of a reversing chamber so that all of the blades of the turbine may simultaneously be employed in developing power.

A further object is to produce a new and improved form of reversing chamber which is provided with a central portion so formed 25 as to discharge steam directly into the exhaust passages of the turbine.

These and other objects are attained by 30 means of a turbine embodying the features herein described and illustrated in the drawings accompanying and forming a part hereof.

In the drawings: Fig. 1 is a fragmental 35 sectional plan view of a turbine embodying my invention, the section being taken along the line 1—1 of Fig. 2.

Fig. 2 is a sectional view along the line 40 2—2 of Fig. 1.

Reentry turbines are frequently constructed with nozzles and reversing chambers distributed throughout the entire circumference of the rotor. Ordinarily a part 45 only of these are operated under light load conditions, but under full overloads all are brought into operation. By means of my invention, reentry turbines may be constructed to efficiently carry additional loads 50 even though the rotor wheel is completely surrounded by the usual arrangement of nozzles and reversing chambers and each of these nozzles is operating at full capacity.

The capacity of the turbine and the range of loads under which it will operate efficiently are thereby increased. 55

In Fig. 1 of the drawings I have more or less diagrammatically illustrated a developed section of a portion of a reentry turbine. As shown, a nozzle 5 is adapted to expand motive fluid, hereinafter called steam, and to discharge it at high velocity into the blades 6 of the turbine. As illustrated, the blades 6 are of the impulse type and are mounted on the periphery of a 60 rotor wheel 7, from which they project radially.

The steam in passing through the row of blades 6, gives up a portion of its velocity energy to the blades and is received by 70 a reversing chamber 8 which is located on the opposite side of the row of blades from the nozzle 5. The reversing chamber 8 is so formed as to receive steam with as little shock as possible and to gradually reverse 75 its direction and deliver it again to the blades 6 at a point farther along on the periphery of the wheel 7. Additional reversing chamber may be employed for receiving and again redirecting the steam into 80 the blades.

The reversing chamber 8 illustrated is substantially U-shape in developed plan view, the steam entering one leg of the U and is discharged from the other. The intervening central portion 10 of the reversing chamber is ordinarily not used, consequently the blades 6 do not receive steam while passing this space. As shown, I have provided an auxiliary nozzle 9 opposite the 90 central portion 10 of the reversing chamber. This nozzle is preferably adapted to expand the steam down to exhaust pressure and to discharge it into the blades 6 at a point between the inlet and the outlet of the reversing chamber 8, that is, at a point opposite the ordinarily unused central portion 10. The steam issuing from the nozzle 9 is discharged from the blades 6 into the central portion 10 of the reversing chamber, which, 100 as shown, is formed like a scoop and discharges the steam received by it directly into the exhaust space within the casing of the turbine. This construction is shown in Fig. 2.

With the construction illustrated prac-

tically all of the blades on the rotor wheel 7 may be simultaneously receiving steam, consequently the turbine is capable of developing a large amount of power in proportion to its size, since dead or inactive spaces are eliminated. The best efficiency in a turbine such as illustrated, is obtained when the nozzles receive steam at substantially full pressure, consequently the total power output can be varied more economically by cutting in or out one or more of the nozzles than by varying the initial steam pressure. As the number of nozzles is increased by the introduction of the auxiliary nozzles 9, the economical power range of the turbine is consequently increased. Obviously, the auxiliary nozzles may be designed to operate with highest efficiency on steam having a different initial pressure from that delivered to the main nozzles.

While I have described and illustrated but one embodiment of my invention, it will be apparent to those skilled in the art that various changes, modifications, additions and omissions may be made in the apparatus described and illustrated without departing from the spirit and scope of the invention, as set forth by the appended claims.

What I claim is:

- 30 1. In a turbine, the combination, with a single row of moving impulse blades and means cooperating therewith whereby velocity energy of motive fluid is successively abstracted in two steps at separated peripheral portions of the turbine, of auxiliary means for impinging high velocity motive fluid against the blades between said separated portions for energy abstraction in a single step.
- 40 2. In a turbine having an exhaust passage, a rotor wheel, blades mounted thereon, nozzles for delivering motive fluid to the blades, reversing chambers for redirecting the motive fluid to the blades, and auxiliary nozzles for delivering motive fluid to the blades at a point opposite the central portion of each reversing chamber, said central portion being formed to direct said motive

fluid received by it to the exhaust passage of the turbine.

3. A reentry turbine having a bladed rotor wheel, nozzles and reversing chambers for normal operation, and auxiliary nozzles for delivering motive fluid to the bladed rotor wheel at intermediate points of the reversing chambers and on the opposite side of the rotor wheel.

4. In a reentry turbine having an exhaust passage, a rotor wheel, blades mounted thereon, a reversing chamber receiving motive fluid from the blades and redirecting it back to the blades, and a central portion formed between the inlet and outlet of the chamber receiving motive fluid from the blades and directing it to the exhaust passage of the turbine.

5. In a reentry turbine, a row of rotating blades, a nozzle for delivering motive fluid to said blades, a reversing chamber receiving motive fluid discharged from the blades and redirecting the fluid so received and delivering it to said blades, and having a scoop shaped central portion in direct communication with the exhaust, in combination with a motive fluid delivery nozzle for delivering motive fluid to said blades and so located that the fluid delivered is discharged by the blades into said central portion.

6. In a turbine, a rotor, working elements mounted on the rotor, a nozzle for delivering motive fluid to the working elements, a reversing chamber having separate inlet and outlet ports for receiving motive fluid from the elements and for redirecting it into the elements, and an auxiliary nozzle for delivering motive fluid to the elements between the inlet and outlet of the reversing chamber to develop increased power.

In testimony whereof, I have hereunto subscribed my name this 12th day of June, 1918.

HENRY F. SCHMIDT.

Witness:

C. W. McGHEE.
